Primary Examiner—Robert M. Spear(74) *Attorney, Agent, or Firm*—Laura M. Hagan; Kerrick, Grise, Stivers & Coyle(57) **CLAIM**

I claim the ornamental design for a patch cable storage cabinet, as shown and described.

DESCRIPTION

FIG. 1 is a perspective view of a patch cable storage cabinet showing my new design;

FIG. 2 is a top perspective view of the front plate of a patch cable storage cabinet, shown removed from the cabinet for ease of disclosure;

FIG. 3 is a front elevation view thereof shown with the front plate removed for ease of disclosure;

FIG. 4 is a rear elevation view thereof;

FIG. 5 is a top plan view thereof shown with the front plate removed for ease of disclosure, the bottom view being a mirror image of that shown; and,

FIG. 6 is a left side elevation view thereof; the right side view being a mirror image of that shown.
